SUPersonic HETERODYNE RECEIVER

Charles Percy Osborne, Hillingdon, England, assignor to Electric and Musical Industries Limited, Hayes, England, a company of Great Britain

Application February 12, 1934, Serial No. 710,804
In Great Britain February 13, 1933

6 Claims. (Cl. 250—20)

The present invention relates to supersonic heterodyne receivers for wireless or like reception. In receivers of this kind an incoming carrier, modulated with a signal, and of a frequency which will hereinafter be referred to as the signal frequency, is caused to beat with a locally generated oscillation, the frequency of which will be called the oscillator frequency, and the resulting beats are detected and fed to the input of an intermediate frequency amplifier tuned to the beat or intermediate frequency. The output from this amplifier is rectified in a second detector to yield the signals.

Difficulty is experienced, particularly with receivers suitable for ultra-short wave working in which the signal frequencies are very high, due to variations in the oscillator frequency. Quite a small change in the oscillator frequency gives rise to a very large percentage change in the intermediate frequency. Another difficulty met with is the extreme sharpness with which circuits tune to these high frequencies.

One way in which these difficulties have been dealt with hitherto is by giving the intermediate frequency amplifier a band-pass characteristic, which is much wider than would normally be desired. For example, when receiving a signal frequency of 90 megacycles/sec. modulated with a drift of 90 kilocycles/sec., the band width may be made 100 kilocycles/sec. thus permitting a drift of 90 kilocycles/sec. which is still only one part in a thousand and may well happen in practice. This wide band width also assists tuning control but on the other hand it seriously reduces the available amplification per stage in the intermediate frequency amplifier and increases the ratio of interference to signal.

It is an object of the present invention to provide means for improving the constancy of the oscillator frequency.

According to the present invention, a supersonic heterodyne receiver is provided with means for generating a harmonic of the intermediate frequency and means for utilizing this harmonic to reduce variations in the oscillator frequency.

The invention will be described by way of example with reference to the accompanying drawings, wherein Fig. 1 shows one embodiment of the invention; Fig. 2 shows another form thereof; Fig. 3 shows still another modification.

Referring to Fig. 1 of the drawings, a superheterodyne receiver comprises a grounded antenna circuit 1 feeding an amplifier 2, tuned to the signal frequency (f_s). The outputs from the amplifier 2 and from thermionic means 3 for

generating oscillations of the oscillator frequency (f_0) are fed to a first detector 4 for rectifying the beats between f_s and f_0 , thereby producing the intermediate frequency (f_1), an intermediate frequency amplifier 5 being provided to which the output from the first detector is fed. A second detector 6 serves to demodulate the intermediate frequency f_1 and a further amplifier 7 is provided for amplifying the modulation frequencies.

The whole or a part of the output voltage of the intermediate frequency amplifier 5 is applied between the control grid 8 and the cathode 9 of an auxiliary thermionic valve 10; that is to say, oscillations of a frequency f_1 are produced in the control grid circuit of this valve. The control grid 8 is given a suitable negative biasing potential relatively to the cathode 9 by means of a battery 11, for example. Between the screening grid 12 and cathode 9 of the valve 10 is arranged a parallel resonant circuit 13 tuned to a harmonic of f_1 , namely a frequency mf_1 , where m is an integer.

The screening grid 12 is maintained at a suitable positive potential with respect to the cathode 9. The anode 14 of the valve is connected to its cathode through a parallel resonant circuit 15 tuned to the oscillator frequency f_0 , and a source 16 of anode current in series. The frequencies up to 5,000 cycles/sec., the band width of f_0 is made equal to a harmonic of 30 may be made 100 kilocycles/sec. thus permitting a drift of 90 kilocycles/sec. which is still only one part in a thousand and may well happen in practice. This wide band width also assists tuning control but on the other hand it seriously reduces the available amplification per stage in the intermediate frequency amplifier and increases the ratio of interference to signal.

It is an object of the present invention to provide means for improving the constancy of the oscillator frequency.

According to the present invention, a supersonic heterodyne receiver is provided with means for generating a harmonic of the intermediate frequency and means for utilizing this harmonic to reduce variations in the oscillator frequency.

The invention will be described by way of example with reference to the accompanying drawings, wherein Fig. 1 shows one embodiment of the invention; Fig. 2 shows another form thereof; Fig. 3 shows still another modification.

Referring to Fig. 1 of the drawings, a superheterodyne receiver comprises a grounded antenna circuit 1 feeding an amplifier 2, tuned to the signal frequency (f_s). The outputs from the amplifier 2 and from thermionic means 3 for

Now we have $f_s - f_0 = f_1$, and $f_0 = Kf_1$. Suppose f_0 changes to $(1+a)f_0$ where a is a positive or negative fraction, then the change in f_0 is $+af_0$, the change in f_1 is $-af_0$ and the change in the control frequency delivered by the auxiliary valve is $-Kaf_0$. Thus a change in frequency of the oscillator of $+af_0$ is accompanied by a change of $-Kaf_0$ in the control frequency; that is to say the control frequency changes K times as much in the opposite sense, and by suitable

coupling can therefore be made to prevent changes in oscillator frequency.

In one example $f_0=36$ and $f_1=6$, both in megacycles/sec. In order to obtain a control frequency from f_1 it is therefore necessary to select the 6th harmonic ($K=6$) and this may be done, for example, by generating and selecting the 3rd harmonic of f_1 , that is 18 megacycles, in the screen grid circuit of the auxiliary valve ($m=3$) and by generating the second harmonic of 18 megacycles, that is 36 megacycles, in the anode circuit ($n=2$). In this case any change in oscillator frequency is accompanied by a change in the control frequency of six times the amount in the opposite sense.

In a modified receiver according to the invention, as shown in Fig. 2, the functions of the oscillator valve and the auxiliary valve are performed by a single valve 20, which may be a so-called heptode in which five grid electrodes are arranged between the cathode and an anode. In such an arrangement, the second grid 21, if that adjacent the cathode be named the first, is connected to the cathode through a resonant circuit 22 tuned to the oscillator frequency, in series with a source of anode current 23 and the circuit of the first grid 24 includes a coupling coil 25, the first and second grids co-operating with the cathode to generate the oscillator frequency.

The third and fifth grids are connected together, and the anode 26 is connected to the cathode through a circuit 27 coupled to that in the second grid circuit and tuned to the same frequency, that is, the oscillator frequency, and the source of anode current in series. The whole or a part of the output voltage of the intermediate frequency amplifier is applied between the fourth grid 28 and the cathode, and the third and fifth grids are connected through a circuit 29 tuned to a multiple of the intermediate frequency and a sub-multiple of the oscillator frequency to a point in the anode current source. The operation of this arrangement is very similar to that already described with reference to the apparatus shown in Fig. 1; the oscillator frequency is made a harmonic of the intermediate frequency, and this harmonic is generated in the anode circuit of the valve and serves to control the generation of the oscillator frequency.

In this arrangement, and in that previously described, it is desirable that the magnitude of the coupling necessary for the generation of the oscillator frequency should be as weak as possible in order that the oscillator may be readily locked in step with the controlling frequency generated in the anode circuit of the auxiliary valve, or of the heptode valve.

In an alternative arrangement shown in Fig. 3 in which a single valve serves both as the oscillator valve and as the auxiliary valve, a thermionic tetrode 30 is so connected as to function as a dynatron oscillator. The potentials applied, relative to the cathode, to the anode 31 and screening grid 32 are so adjusted that the anode-cathode path of the valve has a negative resistance characteristic. Oscillations at the intermediate frequency are fed to the control grid circuit, and the screening grid circuit comprises a resonant circuit 33 tuned to a harmonic of this frequency. The anode circuit comprises a circuit 34 tuned to the oscillator frequency, which is arranged to be a harmonic of the frequency of the oscillations generated in the screening grid

circuit, and the oscillations generated in the anode circuit are fed to the first detector.

The resonant circuits in which the harmonics of the intermediate frequency are generated should, in all cases, preferably be of low decrement in order that substantially only the desired harmonic frequencies are generated. By making these circuits sharply tuned, the tendency for the oscillator frequency to be affected by harmonics of frequencies occurring in the intermediate frequency side bands is prevented.

The invention is of particular value in the case of apparatus adapted for the reception of signals representing a picture or scene and a sound accompaniment, in which the two sets of signals are transmitted at different carrier frequencies, and in which a single oscillator is used to provide both intermediate frequencies.

Where it is desired to make the receiver tunable over a range of signal frequencies, means may be provided whereby the circuits tuning to the frequencies f_s and f_0 have their resonant frequencies changed simultaneously in the proper proportion by the actuation of a single control member 35. Thus the circuit tuning to f_s is made to be resonant always at a frequency $(1+K)$ times the frequency to which the intermediate frequency amplifier is tuned and, of course, the oscillator frequency is maintained equal to Kf_1 .

I claim.

1. The method of maintaining a receiver of the heterodyned type in tune to the received wave which includes the steps of, beating said wave with local oscillations to produce oscillations of a difference frequency, multiplying said oscillations of a difference frequency and entraining said local oscillations with said multiplied oscillations.

2. The method of maintaining a receiver of the heterodyned type in tune to the received wave, which includes the steps of, beating said received wave with local oscillations to produce oscillations of an intermediate frequency, increasing the frequency of said intermediate frequency oscillations to a value substantially equal to the frequency of the local oscillations and superimposing said oscillations of increased frequency on said local oscillations.

3. The method of reducing the amount of shift produced in the intermediate frequency of a receiver of the heterodyned type when the received wave shifts in frequency, which includes the steps of, beating said received wave with local oscillations to produce oscillations of an intermediate frequency, multiplying the frequency of said intermediate frequency oscillations to a value substantially equal to the frequency of the local oscillations and entraining said local oscillations with said oscillations of multiplied frequency.

4. In a heterodyned receiver, the combination of a first detector responsive to signal waves to be demodulated, an oscillator coupled to said first detector, a utilization circuit coupled to the output circuit of said first detector and a frequency multiplier having its input circuit coupled to the output circuit of said first detector and its output circuit coupled to said local oscillator.

5. In a receiver as defined in claim 4, said multiplier comprising a tube provided with a cathode, negative grid, plate and positive screen between the grid and plate, said multiplier output circuit being connected between the plate and cathode and being tuned to the frequency of the oscillator, a resonant circuit connected to the said screen and plate circuit of the said tube and being tuned

to a frequency bearing a predetermined harmonic relation to the oscillator frequency and the first detector output circuit frequency, and said multiplier input circuit being connected between the grid and cathode.

5. In a receiver as defined in claim 4, said multiplier including a screen grid tube, and a reso-

nant network connected between the screen grid and output circuit of the multiplier tube which is tuned to a frequency bearing a predetermined harmonic relation to the frequencies of the oscillator output energy and the first detector output 5 energy.

CHARLES PERCY OSBORNE.
